CLAIM

The ornamental design for a phone lanyard, as shown and described.

DESCRIPTION

FIG. 1 is a first perspective view of a phone lanyard showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded view of the phone lanyard thereof; and,

FIG. 10 is a perspective view of the phone lanyard thereof in another configuration.

The broken lines show portions of the phone lanyard that form no part of the claimed design.
